E. PENBERTHY

LUBRICATION OF TOOLS

Filed Jan. 27, 1925

Fig. 1

Patented Jan. 29, 1929.

UNITED STATES PATENT OFFICE.

ERNEST PENBERTHY, OF DETROIT, MICHIGAN, ASSIGNOR TO CHICAGO PNEUMATIC TOOL COMPANY, OF NEW YORK, N. Y., A CORPORATION OF NEW JERSEY.

LUBRICATION OF TOOLS.

Application filed January 27, 1925. Serial No. 5,003.

- This invention relates to tools having a reciprocating element, such as percussive tools, particularly of the fluid pressure type, and more specifically to the manner of and means for lubricating the working parts thereof. It represents an improvement upon and further development of a similar invention disclosed in my copending application Serial No. 674,443 filed Nov. 12, 1923.
- 10 Among the objects of the invention are to provide effective and adequate lubrication of the parts of tools of the described type but to prevent flooding and waste of lubricant when the tools are not in operation, to facilitate the removal of any foreign matter which might clog the lubricating system, and in general to improve prior arrangement of this character in the interest of more efficient and satisfactory service.
- 15 20 In order to illustrate the invention and the manner of its operation concrete embodiments thereof are shown in the accompanying drawings in which:
- Fig. 1 is a longitudinal vertical sectional view of a hammer drill embodying the invention.
- Fig. 2 is a detail sectional view of a portion of the drill shown in Fig. 1 but showing the throttle valve in a different position.
- 25 30 Fig. 3 is a transverse sectional view substantially on the line 3—3 of Fig. 1; and
- Fig. 4 is a partial longitudinal sectional view similar to Fig. 1 showing a modification.
- The invention is disclosed for the purpose 35 of illustration as embodied in a percussive rock drill of the fluid pressure type having a cylinder 5 provided with a front head 6 and back head 7 held in assembled relation in the usual manner as by side or through rods 8 (Fig. 3). Within the piston chamber 9 of cylinder 5 the impact member or piston 10 reciprocates under the impulse of motive fluid under pressure which enters the tool at 11 (Fig. 3) under the control of a manually operated throttle valve 12 actuated by handle 13, by which valve the motive fluid is admitted through opening 14 to a passage 15 which leads to an automatic distributing valve (not shown) arranged to admit the motive fluid 40 to the piston chamber alternately above and below piston 10 through ports 16 and 17 respectively. An extension 10^a of piston 10, guided by the block or guide sleeve 18, reciprocates in the front head 6 and imparts 45 50 55 blows to a working tool or drill bit 19 re-
- movably supported in a chuck 20 rotatively mounted in the front head. Extension 10^a has vertical ribs 10^b cooperating with grooves in a rotative sleeve 21 keyed to chuck 20 whereby by rotation of the piston is imparted to the 60 drill bit. In the form shown the piston is rotated by the usual rifle bar mechanism comprising rifle bar 22 rotatively mounted in bearings in the back head 7 and cylinder ring 23 and cooperating with a rifle nut 24 secured 65 in the cylindrical bore 25 of the piston, the rifle bar having thereon a pawl carrier 26 which fits in a chamber in the back head and has pawls arranged for cooperation with a ratchet ring 27 in the head.
- 70 75 By reason of the high speed at which a percussive tool of this type operates and the friction developed by the cooperating parts of the rotating mechanism, frequent and adequate lubrication is a necessity in preventing 80 rapid wear, but it is highly desirable that the lubricant should not flood the piston chamber since such a condition clogs and impairs the efficient operation of the drill. The lubricating system, comprising the present invention, 85 which is now about to be described is designed to provide adequate lubrication of all working parts but to prevent access of lubricant to the working parts when the drill is not in operation. The chamber or reservoir for oil 90 or other fluid lubricant may be in any suitable or desired position in the tool; it is preferable, however, but not essential, that the outlet be disposed above the reservoir so that the lubricant must be forced against gravity. 95 In the present instance the oil reservoir 28 is positioned in the guide sleeve 18 or between it and the cylinder wall, the same being arranged to be filled with oil 29 through an opening closed by plug 30. A passage adapted to be made continuous when the drill is in operation leads from reservoir 28, this passage comprising passage 31 in cylinder 5, the end of which registers with a passage 32 in the back head 7 which leads upwardly and 100 across the latter and then downwardly terminating adjacent the throttle valve 12, a groove 33 in the throttle valve which connects passage 32 in one position of the valve with another passage 34 in back head 7 which in turn registers with a bore or passage 35 in the ratchet ring 27. The flow of fluid through the passage comprising the parts enumerated above is limited at at least one point by suitable means which may take the form of a plug 105 110

36 threaded into a bore 36' intersecting passage 32 in back head 7, the plug having a reduced longitudinal bore 36" which forms a portion of the lubricant passage. As indicated this plug is readily removable for cleaning without disassembling any of the parts of the drill.

The groove 33 in the throttle valve 12 places the lubricant passage under control 10 of the throttle valve and it is to be noted that this groove is so positioned relative to the inlet opening 14 that the passage from the lubricant reservoir 28 is made continuous or established only when the drill is in operation 15 (Fig. 1) and is broken or interrupted when the drill is not in operation (Fig. 2).

With the parts in the position shown in Fig. 1 there is a continuous passage from the lubricant reservoir 28 to the pawl and ratchet 20 chamber of back head 7. Communication is intermittently established between this chamber and the piston chamber by a groove 37 in the cylinder ring 23 (Figs. 1 and 3) which is alternately covered and uncovered by the 25 radial extensions of the pawl carrier 26. In normal operation the rifle bar 22 rotates with the piston 10 during one stroke in a counter clockwise direction (Fig. 3) at high speed and the groove 37 makes the ratchet chamber 30 and consequently the lubricant passage extending therefrom to the lubricant chamber subject to the fluctuations of pressure in the piston chamber. In consequence during the down stroke of the piston pressure fluid enters the lubricant passage and some of it reaches the lubricant chamber and builds up 35 pressure in the same so that when the piston reaches the outer limit of its working stroke (Fig. 1) and uncovers the main exhaust port 40 38 the sudden drop in pressure in the piston chamber causes the lubricant to fill the passage and spurt into the ratchet chamber to lubricate the parts therein whence it finds its way through the groove 37 around the reduced neck of the rifle bar, and thence to the 45 sides of the piston chamber and along the rifle bar and is carried by the motive fluid to the rotating parts of the front head.

A modification of the invention is shown 50 in Fig. 4 wherein a throttle valve 12' of slightly different form is used. This throttle valve has a restricted port 39 communicating with the interior of the throttle valve and with a groove 33' corresponding to groove 33 in 55 valve 12 of Fig. 1. By this arrangement the throttle valve 12' can be adjusted so that the lubricant chamber communicates only with the motive fluid supply within the valve as indicated by the dotted line position of valve 60 12' in Fig. 4. With the valve so disposed the lubricant in the reservoir is gradually displaced by the motive fluid and the lubricant so displaced enters the throttle valve and is carried by the motive fluid into the drill. By 65 shifting the valve 12' to the full line position

of Fig. 4 the lubricant chamber is placed in communication both with the piston chamber and with the motive fluid inlet so that a portion of the lubricant spouting from the lubricant passage follows the course outlined in the discussion of Figs. 1-3 into the piston chamber and a portion enters the valve 12' and is carried by the motive fluid to the automatic distributing valve (not shown) and thence into the drill.

While the forms of the invention herein disclosed are at present the preferred embodiments, it is to be understood that they are illustrative only and that the invention includes all modifications and adaptations coming within the scope of the appended claims.

I claim:

1. In a fluid pressure tool having a piston chamber, a piston reciprocable therein, motive fluid conduits leading to said chamber, means for manually controlling the admission of motive fluid to said conduits, a lubricant chamber, a passage under control of said means for establishing communication between said chambers, and means providing a restriction for said passage, said last named means being readily removable for cleaning purposes without disassembling the tool.

2. In a fluid pressure percussive tool having a piston chamber, a piston reciprocable therein, motive fluid conduits leading to said chamber, means for manually controlling the admission of motive fluid to said conduits, a lubricant chamber, a passage under control of said means for establishing communication between said chambers, and means in said passage providing a continuously open conduit therethrough of restricted size, said last named means being accessible for cleaning without disassembling the tool.

3. In a percussive tool having a piston chamber and an impact piston reciprocable therein, a lubricant chamber, said last named chamber being closed save for a passage terminating above the same and adjacent parts to be lubricated, means intermittently establishing communication between said passage and the piston chamber, and a plug mounted in a bore intersecting said passage, for limiting the movement of fluid through said passage, said plug being removable without disassembling the tool.

4. In a percussive tool having a piston chamber, a piston reciprocable therein, means for admitting motive fluid to said tool, a lubricant chamber, a passage under control of said means for establishing communication between said chambers, a plug intersecting said passage and arranged to permit continuous flow of fluid therethrough but in limited amount, said plug being readily removable without disassembling the tool.

5. In a fluid pressure operated tool, a piston chamber, a piston reciprocable therein, a valve for controlling the pressure fluid, a lu-

- bricant chamber, a passage extending from said chamber, and means under control of said valve for establishing connection of said passage separately with both said piston chamber and the pressure fluid inlet when the valve is in tool operating position.
6. In a fluid pressure operated tool having a piston chamber, a piston reciprocable therein, conduits leading to said chamber, means including a throttle valve for controlling the admission of motive fluid to said conduits to operate said piston, a lubricant chamber, passages extending from said chambers respectively, and means operating in response to the operation of said throttle valve for making or interrupting the connection between said passages and between said passages and the motive fluid inlet.
7. In a fluid pressure operated tool having a piston chamber, a piston reciprocable therein, conduits leading to said chamber, means including a throttle valve for controlling the admission of motive fluid to said conduits to operate said piston, a lubricant chamber, passages extending from said chamber respectively and terminating adjacent said valve, said valve having a groove for establishing connection between said passages in one position of said valve and having a bore intersecting said groove for connecting said passages with the motive fluid inlet.
8. In a fluid pressure operated tool having a piston chamber, a piston reciprocable therein, conduits leading to said chamber, means including a throttle valve for controlling the admission of motive fluid to said conduits to operate said piston, a lubricant chamber, passages extending from said chambers respectively and terminating adjacent said valve, said valve having a groove for establishing connection between said passages in one position of said valve and having a bore intersecting said groove for connecting said passages with the motive fluid inlet, and a plug intersecting one of said passages and arranged to limit the flow of fluid therethrough.
9. In a fluid pressure operated tool having a piston chamber, a piston reciprocable therein, a throttle valve for controlling the admission of motive fluid to said tool to operate said piston, a lubricant chamber, passages extending from said chambers respectively and terminating adjacent said valve, said valve having a groove for establishing connection between said passages in one position of said valve and having a bore intersecting said groove for connecting said passage with the motive fluid inlet, and a plug inter-
- secting one of said passages and arranged to limit the flow of fluid therethrough, said plug being readily removable without disassembling the tool.
10. In a fluid pressure operated tool, a lubricant chamber, a passage extending thereto, means for selectively establishing connection between said passage and the pressure fluid inlet, and means inserted in said passage providing a continuously open connection of restricted size therethrough, said last named means being removable for cleaning without disassembling the tool.
11. In a pneumatic hammer drill having a cylinder, a cylinder ring closing one end thereof, a front head for the other and a rotatable chuck for a working tool in said front head, a hammer piston reciprocable within said cylinder and keyed to said chuck, rifle bar rotation mechanism mounted in said backhead for coaction with said piston, a throttle valve for controlling the pressure fluid, and means for lubricating the moving parts in synchronism with the reciprocation of said piston comprising a lubricant reservoir adjacent said front head, a passage from said reservoir under control of said valve leading to said backhead and terminating adjacent said rotation mechanism, and means under control of said mechanism for intermittently establishing connection between said passage and the piston chamber.
12. In a pneumatic hammer drill having a cylinder, a cylinder ring closing one end thereof, a front head for the other end, a rotatable chuck for a working tool in said front head, a hammer piston reciprocable within said cylinder and keyed to said chuck, rifle bar rotation mechanism mounted in said backhead for coaction with said piston, a throttle valve for controlling the pressure fluid, and means for lubricating the moving parts in synchronism with the reciprocation of said piston comprising a lubricant reservoir adjacent said front head, a passage from said reservoir under control of said valve leading to said backhead and terminating adjacent said rotation mechanism, means under control of said mechanism for intermittently establishing connection between said passage and the piston chamber, and a plug mounted in a bore intersecting said passage for limiting the flow of fluid therethrough, said plug being readily removable without disassembling said tool.

Signed by me at Detroit Mich., this 16th 115
day of January, 1925.

ERNEST PENBERTHY.
